UNITED STATES PATENT OFFICE.

LACEY BABOS, OF PORTLAND, OREGON, ASSIGNOR TO AMERICAN LIQUID METER COMPANY, OF PORTLAND, OREGON, A CORPORATION OF WASHINGTON.

FRACTIONAL COUNTER.

Application filed November 7, 1921. Serial No. 513,350.

To all whom it may concern:

Be it known that I, LACEY BABOS, a citizen of the United States, and resident of the city of Portland, in Multnomah County, 5 State of Oregon, have invented certain new and useful Improvements in Fractional Counters, of which the following is a specification.

In machines which have a reciprocating 10 operating part, the output of the machine being controlled thereby or in accordance therewith, and in which the reciprocating part is double-acting—that is, it causes delivery on both strokes—it is highly desirable 15 at times to halt the machine's operation at some point intermediate the ends of a stroke, and yet to know the exact output of the machine. It is an object of my invention to provide means whereby the output of such 20 a machine, as for instance, a fluid meter, may be accurately determined, irrespective of what part of a stroke the reciprocating element may have completed, and following movement in either direction.

25 More specifically my object is to provide a spindle operatively connected to a counter mechanism and acted upon through movement of the piston of a piston type fluid meter to be rotated in a single direction by 30 the reciprocating movement of the piston in either direction.

My invention comprises those novel parts and combinations thereof which are shown 35 in the accompanying drawings, described in the specification and particularly defined by the claims terminating the same.

In the accompanying drawings I have shown my invention in the form which is now preferred by me.

40 Figure 1 is an axial section through a piston type meter embodying my invention, parts being broken away or omitted.

Figure 2 is a transverse section through one end of the meter.

45 Figure 3 is a detail section of a part of my mechanism.

Figure 4 is an axial section through the connection between the reciprocating piston and the rotating spindle, taken on line 4—4 50 of Figure 5.

Figures 5 and 6 are transverse sections through the same device on the lines 5—5 and 6—6, respectively, of Figure 4.

Figure 7 is a section showing a detail of my mechanism. 55

The particular form of meter with which my device is shown as associated forms no part of my present invention, and may be any which is found suitable. This meter is similar to that shown in Patent No. 1,355,208 60 to Carlos J. Bassler. It comprises, briefly, a cylinder 9 within which a piston 90 reciprocates under the influence of the fluid pressure in the meter. Valves, which are not shown herein, regulate the movement of the piston 90 and determine the point of reversal of its stroke and thereby the output of the meter. Likewise the counting mechanism which I have indicated at 8 may be of any suitable type, being of that general 70 class which is operated by rotation in one direction only. This is shown as secured in a trough 91 on the upper side of the cylinder 9 so that it is accessible and easily readable.

A spindle 1 is mounted preferably parallel 75 to the axis of the cylinder 9. It is shown herein as within the cylinder and passing through an aperture provided in the piston 90, although it might well be outside of the path of the piston and suitably connected 80 thereto. This spindle 1 is provided with a right-hand groove 10 and a left hand groove 11 extending from end to end and of a pitch preferably equal to the stroke of the piston 90, or a multiple thereof. The exact pitch 85 is determined by the counter 8 to be employed, and the rotational effect desired thereupon.

The ends of the spindle are journaled 90 within sleeves 5 which are secured in the heads 92 of the cylinder. A bevel gear 12 is supported between a bracket 13 and an extension 51 of a sleeve 5 to prevent its movement axially of the cylinder. The gear 12, as is best shown in Figure 7, is provided 95 with a feather key 14 which engages within an axially extending slot 15 in the end of the spindle 1. The bevel gear 12 meshes with a gear 17, and through other suitable means connects with a shaft 16 which projects from 100 the counter 8.

The spindle 1 has thrust bearings at its ends within the sleeves 5, and these bearings, and consequently the spindle, are arranged to be adjusted longitudinally to coordinate 105 the spindle's position with the stroke of the

piston 90 for a purpose to be later explained. A stem 52 is threaded in each of the sleeves 5 and is provided with a hardened ball point 53 engaging the end of the spindle 1 and forming the thrust bearing therefor. By adjusting the two stems 52 within their respective sleeves with a screw-driver the position of the spindle 1 within the cylinder is adjusted axially thereof. The outer ends of the sleeves 5 may be closed with plugs 54 if desired.

Secured in the aperture in the piston through which the spindle 1 passes is a sleeve 4. This is a close fit within the aperture of the piston in order to prevent leakage from one side to the other, thereof. Within the sleeve 4 are rotatably mounted nuts 2 and 3, the first having a left-handed feather 25 and the other a right-handed feather 35. These two nuts are entirely separate and independent one from the other. The feather 25 is adapted to engage the left hand groove 10 and the feather 35 the right hand groove 11.

25 A ratchet device connects each of the nuts 2 and 3 with the sleeve 4. These ratchet devices are oppositely set so that while the nut 2, for instance, is being held against rotation, the nut 3 is free to rotate, and vice versa. The ratchet device as shown consists of a shoulder 20 upon the nut 2, and 30 upon the nut 3, the two shoulders facing oppositely. The shoulder 20 is engaged by a dog 21 and the shoulder 30 by a dog 31, each of these dogs passing through and being held in apertures 40 of the sleeve 4 so that they may have no movement angularly thereof. Springs 22 and 32 tend to hold their respective dogs in engagement with the shoulders 20.

35 As the piston 90 reciprocates, it carries the sleeve 4 with it. If we consider that movement of the piston starts from the position shown in Figure 1 and goes to the left, one of the nuts, as 2 will be held from rotation by engagement of the dog 21 and the shoulder 20. This will cause rotation of the spindle 1 by reason of the engagement of the feather 25 in the groove 10. This rotation of the spindle 1 and the engagement of the feather 35 in the groove 11 cause reverse rotation of the nut 3. At the end of the piston stroke, however, the shoulder 30 and dog 31 are in position to engage and the reverse movement to the right of the piston 90 causes such engagement and thereby causes rotation of the spindle 1. This time, however, the spindle is acted upon by the right hand nut 3 by movement in the opposite direction, so that its rotation will continue in the same direction as when it was acted upon by the left hand nut 2. The nut 2 in turn will be reversely rotated until at the right hand end of the piston's stroke the shoulder 20 and dog 21 will again be in

position for engagement and the process will be repeated, the spindle 1 turning always in the same direction. Thus if it is found necessary or desirable to stop the action of the meter at any time, the counter 8 70 will register accurately the output of the meter although the piston may not have exactly reached the end of its stroke. Where exact accuracy is desired and particularly where the meter is of large capacity, being 75 able thus to determine the output to the fractional part of the stroke of the piston is a great advantage.

In order that there may be no interference between either of the feathers 25 or 35 and the groove of the other feather, especially where they cross, I have made one of these feathers, as 25, slightly higher than the other and have made the groove 10 into which it fits slightly deeper than the groove 85 11. The feather 25, moving in the groove 10, is never deflected or disturbed by the crossing of the groove 11. The feather 35 however, moving in the shallower groove 11, is made sufficiently long that its ends will 90 overlap the crossing of the grooves 10 and 11 so that no interference can result thereby.

The pitch of the grooves 10 and 11 might readily be greater or less than the stroke of the piston 90 and I do not desire to limit 95 myself to a pitch of this length only. Also, a series of shoulders 20 and 30 might be provided each upon its respective nut if this were for any reason desired.

By mounting the spindle 1 so that it is axially adjustable, it is possible to more exactly position it relative to the stroke of the piston 90 and to cause the dog 31 and the shoulder 30 or the dog 21 and the shoulder 20 to come into engagement at the end 105 of a stroke without any appreciable lost motion, and in this manner to increase the accuracy and reliability of the counter.

What I claim as my invention is:

1. In combination, in a meter having a 110 reciprocable member, mechanism operable by rotation in one direction only, and means operable by movement of the meter member in either direction for causing rotary movement of the mechanism in the single 115 operating direction.

2. In combination, in a meter having a reciprocable element, a counter operable by rotation in one direction only, and means connecting said meter element and the counter for actuation of the latter, said means including two opposed and independent ratchet devices, and means associated therewith for operating said ratchets alternately. 120

3. In combination, in a meter having a reciprocable element, a counter operable by rotation in one direction only, means connecting said meter element and the counter for actuation of the latter, whereby reciprocal movement of the meter element in 125 130

either direction causes rotary movement of the counter in the actuating direction, parts of said connecting means being adjustable to coordinate it with the stroke of the meter element.

4. In combination, in a fluid meter, a reciprocable metering piston, a rotatable spindle having two reversely turned helical grooves, a counter operable by rotation in one direction only, operative connection between said spindle and counter, two nuts, each engageable with its respective one of said grooves and both reciprocable by movement of said piston, and two independent ratchet connections, one to each of said nuts, and operable to permit alternate rotation of said nuts in a single direction only.

5. In combination, in a fluid meter, a reciprocable metering piston having an aperture therethrough, a rotatable spindle passing through said aperture and having two crossed and reversely turned helical grooves, mechanism operable by rotation in one direction only, and operatively connected to said spindle, and means for effecting continuous rotation of said mechanism in a single direction, from the piston, comprising two nuts rotatably mounted in said piston and each engageable with its respective one of said grooves, and two opposed and independent ratchet connections, each between the piston and its respective nut, whereby one nut is held still to rotate the spindle in the counter-actuating direction, thereby causing reverse rotation of the other nut.

6. In combination, in a fluid meter, an element reciprocable in accordance with the flow of fluid through the meter, a counter, and operative connection between said element and counter to cause the latter to indicate the fractional part of the stroke of the element in either direction which has been completed.

7. In combination, in a fluid meter, a reciprocable metering piston, a rotatable spindle having two reversely turned helical grooves, a counter operable by rotation in one direction only, operative connection between said spindle and counter, two nuts, each engageable with its respective one of said grooves and both reciprocable by movement of said piston, and two independent ratchet connections, one to each of said nuts, whereby alternate rotation of said nuts in a single direction only is permitted, and means for adjusting said spindle longitudinally to coordinate it with the piston stroke.

8. In combination, in a fluid meter, a meter element reciprocable in accordance with the flow of fluid through the meter, a counter operable by rotation in one direction only, a rotatable spindle having a right-hand and a left hand helical groove, operative connection between said spindle and

counter, a sleeve reciprocable by movement of said reciprocable meter element, two nuts rotatable and relatively axially positioned within said sleeve, and each engageable with its respective one of said grooves, and oppositely facing ratchet means, each engageable between said sleeve and its respective nut. 70

9. In combination, in a fluid meter, a meter element reciprocable in accordance with the flow of fluid through the meter, a counter operable by rotation in one direction only, a rotatable spindle having a right-hand and a left-hand helical groove, operative connection between said spindle and counter, a sleeve reciprocable by movement 75 of said reciprocable meter element, two nuts rotatable and axially spaced within said sleeve, and each engageable with its respective one of said grooves, a shoulder upon each nut, the shoulders on the two nuts facing oppositely, and two spring-pressed dogs held in said sleeve against angular movement relative thereto, and each engageable with its respective one of said shoulders. 80

10. In a frictional counter for reciprocating, double-acting mechanisms, a rotative spindle and two independently rotative nuts movable axially of the spindle, said spindle having right-hand threaded engagement with one of said nuts and left-hand threaded engagement with the other nut, and means for alternately holding one nut against rotation to rotate the spindle and permitting rotation of the other nut with 100 the spindle, as the nuts are alternately advanced or retracted along the spindle. 90

11. In combination with a reciprocating, double-acting meter, and mechanism controlled thereby and operable by rotation in a single direction only, a rotative spindle operatively connected to said mechanism, two independently rotative nuts movable axially of the spindle, said spindle having right-hand threaded engagement with one of said nuts and left-hand threaded engagement with the other nut, a sleeve including both of said nuts, and two relatively reversed ratchet means connecting said sleeve each with its respective nut, whereby alternately one nut is held against rotation to rotate the spindle and the other nut is permitted to rotate with the spindle, as the nuts are alternately advanced or retracted along the spindle. 110 105 115

12. In combination with a reciprocating, double-acting meter, and mechanism controlled thereby and operable by rotation in a single direction only, a rotative spindle operatively connected to said mechanism, the spindle having a right-hand and a left-hand helical groove, one of said grooves being of greater depth than the other, and two independently rotative nuts movable axially of the spindle, and each having a feather en- 125 130

gaging its respective groove, and of a depth corresponding thereto, the shallower feather being of a length greater than the width of material cut away at the crossings of the grooves, and means for alternately holding one nut against rotation to rotate the spindle and permitting rotation of the other nut with the spindle, as the nuts are alternately advanced or retracted along the spindle.

10 13. In combination, in a meter having a reciprocable element, mechanism operable by

rotation in one direction only and means connecting said meter element and said mechanism for actuation of the latter, said means being operable to convert reciprocating movement of the meter element into continuous unidirectional rotary movement of the mechanism.

Signed at Portland, Multnomah County, Oregon this 30th day of September, 1921.

LACEY BABOS.
